UNITED STATES PATENT OFFICE

2,213,122

FOAM PRODUCER FOR FIRE
EXTINGUISHERS

Ernst Göhre, Dortmund, Germany, assignor to
Concordia Elektrizitäts - Aktiengesellschaft,
Dortmund, Germany, a joint-stock company of
Germany

Application November 19, 1938, Serial No. 241,361
In Germany September 24, 1938

2 Claims. (Cl. 261—75)

My invention relates to improvements in foam producers for fire extinguishers, and more particularly in foam producers of the type comprising a pair of nozzles opening into a common container having a delivery opening, the said nozzles being connected respectively with a supply of a suitable liquid extinguishing medium and a gas adapted to transform the said medium into a foam which is delivered through said delivery opening. The object of the improvements is to provide an apparatus of this type in which the formation of dead spaces in which water is accumulated is prevented. Another object of the improvements is to provide an apparatus in which the loss of pressure within the said receptacle is reduced to a minimum. With these objects in view, my invention consists in constructing the said receptacle substantially in the form of an oval or ovoid or pear, and mounting the said nozzles in the longitudinal axis of the said oval or ovoid body with their openings opposing each other and near the larger end thereof, the delivery opening of the said receptacle being provided at the opposite or narrow end thereof. For the purpose of explaining the invention an example embodying the same has been illustrated in the accompanying drawing in which a longitudinal sectional elevation of the apparatus is shown. In the example shown in the drawing the apparatus comprises a receptacle of oval or ovoid shape composed of two sections *b* and *e* suitably connected with each other at *f*, the said receptacle having a delivery pipe *d* secured to its narrow end at *g*. Axially of the said receptacle *b*, *e* a nozzle *a* is passed through the broad end thereof so as to open into the same near the said broad end, and a second nozzle *c* is passed through the side wall of the body *b*, *e*, the inner or delivery end of the said nozzle being bent at right angles to-

wards the nozzle *a* and being located with its delivery end coaxially of the said nozzle *a* and the receptacle *b*, *e*.

In the operation of the apparatus it is preferred to supply the liquid medium through the nozzle *a* and the gaseous medium through the nozzle *c*. But I wish it to be understood that my invention is not limited to this feature.

The liquid delivered into the receptacle *b*, *e* through the nozzle *a* is impinged upon by the gaseous medium delivered coaxially thereof through the nozzle *c*, and it is transformed thereby into a foam. The said foam flows, without being subjected to stowing, to the pipe *d* and it is delivered therefrom outwardly. No dead spaces in which liquid might accumulate are produced within the receptacle, and any loss of pressure which is not needed for the formation of foam is avoided. Thus the efficiency of the apparatus is high.

I claim:

1. A foam producing apparatus, comprising a receptacle of substantially oval shape and having a delivery pipe at one of its narrow ends extending substantially in the direction of the longitudinal axis of said oval receptacle, and a pair of nozzles for the supply respectively of a liquid and a gaseous medium passed into the said receptacle and having their delivery openings opposed to each other and located substantially coaxially of the longitudinal axis of said receptacle, one of said nozzles being located near the end wall of said receptacle remote from said delivery pipe.

2. A foam producing apparatus as claimed in claim 1, in which the receptacle is ovoid in shape, the delivery opening being provided at the narrower end of the said ovoid and the said nozzles near the broader end thereof.

ERNST GÖHRE. 40
